SET OF PICTURE PLAYING CARDS

Stig Lindberg, Eriksberg, Gustavsberg, Sweden, assignor
to Aktiebolaget J. O. Oberg & Son, Eskilstuna, Swe-
den, a corporation of Sweden

Application March 21, 1958, Serial No. 50,119

Term of patent 14 years

(Cl. D34—13)

The drawings show the front views of the faces of the playing cards embodying the design of my invention.

The cards are of the usual thickness and the backs are conventional.

I claim:

The ornamental design for a set of picture playing cards, as shown and described.
